UNITED STATES PATENT OFFICE.

GEORGE B. EHRMANN, OF TROY, NEW YORK.

COLLAR-SHAPING MACHINE.

1,257,685.

Specification of Letters Patent. Patented Feb. 26, 1918.

Application filed November 14, 1916. Serial No. 131,238.

To all whom it may concern:

Be it known that I, GEORGE B. EHRMANN, a citizen of the United States, residing at Troy, county of Rensselaer, and State of New York, have invented certain new and useful Improvements in Collar-Shaping Machines, of which the following is a specification.

Reference may be had to the accompanying drawings, and the reference characters marked thereon, which form a part of this specification. Similar characters refer to similar parts in the several figures therein.

The type of collar to the treatment of which this invention relates has a standing body with end-wings folded along an oblique line back upon the body of the collar.

The fold thus formed in the collar tends to distort from circular form the end-portions of the collar, and to cause such end-portions each to occupy an independent vertical plane, whereby the front of the collar in use presents an angular appearance instead of curving gracefully around the neck of the wearer.

The principal object of the invention is to cause the end-portions of such a wing-collar to assume and maintain in use substantially the same curved form as the other parts of the collar.

Other objects will appear in connection with the following description.

Figure 1 of the drawings is a view in front elevation of my machine for shaping the ends of a wing-collar.

Fig. 2 is a view of the same in side elevation partly in vertical section.

Fig. 3 is a top plan view of the machine.

Fig. 4 is a front view in perspective of a wing-collar for the shaping of which my machine is adapted.

Fig. 5 is a top plan view of the broken away front-portion of the same.

Fig. 6 is a vertical cross-section of the same taken on the broken line 6—6 in Fig. 5.

Referring to the drawings wherein the invention is shown in preferred form, 1 is the frame of the machine mounted upon a table 2.

50 Supported by the frame 1, is a bed 3, which is one of a pair of pressing-members adapted to press between them an end of a wing-collar.

The coöperative pressing-member 4, is mounted upon a slide-rod 5, which slide-rod is adapted to reciprocate vertically in a

slideway 6, in fixed relation to the frame of the machine.

The lower end of the slide-rod 5, is screw-threaded as shown at 7, and passes freely 60 through an aperture in a bracket 8, in fixed relation to the frame of the machine.

The lower end of the slide-rod 7, is connected by a link 9, with a treadle 10, whereby downward movement of the rod 7, can 65 be accomplished by the foot of the operator.

The slide-rod 5, and pressing-member 4, are yieldingly supported in elevated position by coil-springs 11, interposed between the bottom of the bracket 8, and a nut 12, 70 on a higher screw-threaded portion of the slide-rod.

The pressing-surface of the bed 3, which is preferably made of metal is concaved in the direction of the length of the collar to 75 be treated, and also in a direction transverse of the collar.

The pressing-surface of the coöperative pressing-member 4, is preferably convexed in the direction of the length of the collar 80 to be treated, and also in a direction transverse of the collar.

The bed 3, is preferably heated in some known manner as by means of a gas-burner 13, located beneath the bed.

85 The pressing-member 4, is preferably a form covered or padded with soft fabric, and it is preferably mounted upon a slide-rod, 5, in a yielding manner so that it can automatically adjust itself to the inequalities in the end of the collar, due to differences in thickness by reason of the folded-over wings.

As a means for thus mounting the pressing-member 4, I provide the upper end of 95 the slide-rod 5, with a head 14, upon which the pressing-member 4, is mounted with capacity for vertical movement, by means of four spindles 15, fixed upon the core or form of the pressing-member 4, and playing in apertures in the head 14.

100 Each of the spindles 15, is encircled by a coil-spring 16, interposed between the pressing-member 4, and the head 14.

In Fig. 4, I have shown a collar of the type to the treatment of which my invention relates. 1, is the standing body of the collar, and 2, are the folded-over wings.

The operation of the machines is as follows:

110 Each end of the collar is separately inserted between the pressing-members 3 and

4, with the wing 2, adjacent to the pressing-member 3; and the upper pressing-member 4, is then forced down by means of the treadle 10, to engage the end of the collar 5 and force the same against the concaved surface of the pressing-member 3, to make it conform thereto, the end of the collar being thus held under pressure as long as may be desired or is necessary to fix it in a 10 form corresponding with that of the pressing-members.

The curvature of the pressing-members in the direction of the length of the collar thus imparts to the ends of the collar substantially the same curved form as that of the body of the collar as shown in Fig. 5, giving to the front of the collar a graceful curved form instead of a more or less angular form, as indicated by the dotted lines 17, in 20 Fig. 5.

While the curved form of the pressing-members in the direction of the length of the collar is sufficient to accomplish this result, the curved form of the pressing-members 25 transversely of the collar, as in the preferred form of my invention, causes the corner-portions of the collar at the junction

of the upper ends of the wings with the body of the collar, to curve slightly inward, causing them to fit more closely to the neck of 30 the wearer, instead of flaring away from the neck of the wearer, as is the tendency of such collars.

The form thus imparted to the ends of the collar by the curvature of the pressing-members transversely of the length of the collar is shown in Fig. 6.

Preliminary to the shaping of the ends of the collar in the machine, its ends may be steamed or dampened if desired.

What I claim as new and desire to secure by Letters Patent is:

In a machine for shaping the ends of wing-collars and in combination, a pair of pressing-members adapted to receive between them an end of a wing-collar, said pressing-members having coöperative pressing surfaces, one convexed and the other concaved both in the direction of, and transversely to the length of the collar.

In testimony whereof, I have hereunto set my hand this 11th day of November, 1916.

GEORGE B. EHRMANN.
